SCAFFOLD

Henry G. Roten, Houston, Tex.

Application May 5, 1944, Serial No. 534,297

9 Claims.

(Cl. 304—2)

This invention relates to improvements in scaffolds and more particularly to scaffolds having metallic framework which can be readily erected either at the interior or exterior of a building without having to be attached to the building.

One of the objects of the invention is to provide a structure which can be erected in about one-tenth the time it takes to build a wooden scaffold, and one which is more substantial, safer, and more durable than a wooden scaffold, and in which no part or timbers of the scaffold is wasted when the scaffold is dismantled.

Another object is to supply a scaffold of metal, or the like, which can be readily erected by unskilled labor, and so manipulated that essential elements may extend around corners to take care of side walls of buildings arranged at angles to one another.

With the foregoing objects outlined, and with other objects in view which will appear as the description proceeds, the invention consists in the novel features hereinafter described in detail, illustrated in the accompanying drawings, and more particularly pointed out in the appended claims.

In the drawings—

Fig. 1 is a perspective view of a unit of my improved scaffold, in incomplete condition to facilitate illustration.

Fig. 2 is a similar view of one of the base elements of the structure.

Fig. 3 is a perspective view of a socketed joint element of the structure.

Fig. 4 is a similar view of a turnbuckle forming part of the scaffold.

Fig. 5 is a perspective view of a corner element of the scaffold.

Referring to the drawings, 6 designates base plates having upstanding pegs 7 rigidly connected thereto. Four of these base elements are used at the corners of a unit of the scaffold, and the pegs are adapted to extend into sockets 8 at the lower ends of the joint elements 9. Each of these elements has an upstanding socket 10 coaxial with the axis of the socket 8, and four horizontally disposed sockets 11 radiating from said axis and positioned at 90° relative to one another. The sockets are jointed by webs 12, each of which has an aperture 13 for a purpose hereinafter described.

To complete the base of a unit, horizontal bars or pipes 14 have their ends extending into sockets 11 of four of the units 9 so as to make a complete rectangle. Four vertical rigid posts or pipes 15 have their lower ends supported by the sockets 10, and they are capped by joint elements 9a identical with the elements 9. Other horizontal rods or pipes 16 have their ends connected to horizontal sockets of the elements 9a so as to form a rectangular frame at the top of the unit,

for supporting boards, or the like (not shown) for the support of workmen.

To rigidify the structure, chains 17 are arranged at each side of the unit, each chain having a hook 18 at one end engaging one of the apertures 13. The other ends of the chain are extended through loops 19 of non-rotatable members 20 of turnbuckles, said members having hooks 21 to engage end links of the chains. Each turnbuckle has oppositely pitched threads 22 and 23 engaging internal threads of the members 20 and actuated by a handle 24. It will be obvious that turning of the handle will cause tightening of the chains so as to hold the parts together and render the structure rigid.

Where it is necessary to extend the scaffold around a corner, I use corner elements which I have designed, and one of which is illustrated in Fig. 5. There it will be seen that a bar 25 adapted to be received in any one of the sockets 11, terminates in a horn or hook-shaped extension 26 provided with a series of spaced vertical apertures 27 designed to receive a pin which may also be passed through a hole 28 of a hinge socket 29, secured to the bar by a pivot pin 30. It will be obvious that a pin passed through hole 28 and any one of the holes 27 will act to secure the hinge socket at various angles to the bar 25 so that the socket 31 may be placed in position to receive horizontal bars 14, 16 in extending the structure around a corner, or the like.

From the foregoing, it is believed that the structure, use and advantages of the improved scaffold may be readily understood by those skilled in the art, and it will be apparent that the various elements are detachably connected to one another so that one or more units may be erected by properly assembling the elements. It is also manifest that a unit can be extended from either side of the unit illustrated, by the use of other horizontal bars, and the unit may be increased in height by adding vertical posts to the top sockets of the elements 9a.

While I have disclosed what I now consider to be a preferred embodiment of the invention, it is obvious that changes may be made in the details disclosed without departing from the spirit of the invention, as expressed in the claims.

What I claim and desire to secure by Letters Patent is:

1. A scaffold comprising a unit including socketed joint elements each provided with upper and lower aligned vertical sockets and horizontal sockets radiating from the axis of the vertical sockets of that element, apertured webs rigidly united with the vertical sockets and horizontal sockets, of each element, bars joining said elements and extending into horizontal sockets thereof, posts extending into vertical sockets of the elements, similar joint elements arranged at the tops of the

posts, each post extending into one of the vertical sockets of one of the last mentioned elements, connecting elements connected to the apertured portions of the webs, and turnbuckles each connected respectively to two pairs of the connecting elements and arranged at the sides of the unit for making it rigid.

2. A scaffold comprising a unit including socketed joint elements each provided with upper and lower aligned vertical sockets and horizontal sockets radiating from the axis of the vertical sockets of that element, apertured webs rigidly united with the vertical sockets and horizontal sockets of each element, bars joining said elements and extending into horizontal sockets thereof, posts extending into vertical sockets of the elements, similar joint elements arranged at the tops of the posts, each post extending into one of the vertical sockets of one of the last mentioned elements, chains connected to the apertured portions of the webs, and turnbuckles each connected respectively to two pairs of the connecting elements and arranged at the sides of the unit for making it rigid.

3. A scaffold comprising a unit including socketed joint elements each provided with vertical sockets and horizontal sockets radiating from the vertical sockets, each joint element having external webs connecting its vertical sockets to its horizontal sockets and provided with apertures, bars joining said joints and extending into horizontal sockets thereof to form a frame at the bottom portion of the unit, posts extending into vertical sockets of the joints and rising from the latter, similar joint elements arranged at tops of the posts, each post extending into one of the vertical sockets of one of the last-mentioned elements, horizontal bars extending into horizontal sockets of the joint elements at the tops of the posts, connecting elements engaging apertures of said webs, and turnbuckles arranged substantially parallel to the bars and each connected respectively to two pairs of the connecting elements and arranged at the sides of the unit for making it rigid.

4. A scaffold comprising a unit including socketed joint elements each provided with vertical sockets and horizontal sockets radiating from the vertical sockets, bars joining said socketed joints and extending into horizontal sockets thereof, posts extending into vertical sockets of the joints, similar joint elements arranged at the tops of the posts, each post extending into one of the vertical sockets of one of the last-mentioned elements, horizontal bars extending into horizontal sockets of the joint elements at the tops of the posts, connecting elements connected to the joints, and turnbuckles connected respectively to two pairs of the connecting elements, and arranged at the sides of the unit for making it rigid, each turnbuckle comprising non-rotatable members provided with external loops and hooks, each companion pair of non-rotatable members having oppositely pitched internal threads and a hand-operated screw having oppositely pitched external threads engaging the threads of said members.

5. In a scaffold structure, a joint element provided with a socket, a bar extending into the socket and provided with an apertured horn, a socket member hingedly connected to the bar, means engageable with an aperture of the horn for securing the socket member to the horn at various angles to the bar, said socket member having a socket of substantially the same in-

ternal diameter as the external diameter of the bar.

6. A joint element for scaffolds or the like comprising coaxial top and bottom vertical sockets, other horizontal sockets radiating from the axis of the first-mentioned sockets, and webs integral with said horizontal and vertical sockets and provided with apertures.

7. A scaffold comprising a unit including four corner members, each having a supporting plate and an up-standing peg, socketed joint elements each provided with vertically disposed coaxial sockets, the pegs extending into certain of said sockets, each of said joint elements being also provided with horizontal sockets radiating from the vertical sockets, bars joining said socketed joints and extending into horizontal sockets thereof, posts extending into vertical sockets of the joints, similar joint elements arranged at the tops of the posts, each post extending into one of the vertical sockets of one of the last-mentioned elements, horizontal bars extending into horizontal sockets of the joint elements at the tops of the posts, connecting elements connected to the joints, and turnbuckles each connected respectively to two pairs of the connecting elements, and arranged at the sides of the unit substantially parallel to the bars at that side of the unit for making the unit rigid.

8. A scaffold comprising a unit including socketed joint elements provided with vertical sockets and horizontal sockets radiating from the vertical sockets, bars joining said socketed joints and extending into horizontal sockets thereof, posts extending into vertical sockets of the joints, similar joint elements arranged at the tops of the posts, each post extending into one of the vertical sockets of one of the last-mentioned elements, horizontal bars extending into horizontal sockets of the joint elements at the tops of the posts, connecting elements connected to the joints, and turnbuckles each connected respectively to two pairs of the connecting elements, and arranged at the sides of the unit for making it rigid, said connecting elements and turnbuckles forming substantially H-shaped devices at each side of the unit.

9. A scaffold comprising a unit including socketed joint elements each provided with upper and lower aligned vertical sockets and horizontal sockets radiating from the axis of the vertical sockets of that element, bars joining said elements and extending into horizontal sockets thereof, posts extending into vertical sockets of the elements, similar joint elements arranged at the tops of the posts, each post extending into one of the vertical sockets of one of the last-mentioned elements, horizontal bars extending into horizontal sockets of the joint elements at the tops of the posts, connecting elements connected to the joint elements, and turnbuckles each connected respectively with two pairs of the connecting elements and arranged at the sides of the unit for making it rigid, each turnbuckle comprising internally threaded end members provided with end loops and side hooks, and an intermediate rotatable threaded member in threaded engagement with the threads of the end members, each pair of connecting elements passing through one of said loops and being secured to certain of said hooks.

HENRY G. ROTEN.
